[57] CLAIM

The ornamental design for a pocket organizer for beach chair, as shown.

DESCRIPTION

FIG. 1 is a front perspective view of a pocket organizer for beach chair showing my new design;

FIG. 2 is a front elevational view thereof;

FIG. 3 is a left side elevational view thereof;

FIG. 4 is a right side elevational view thereof;

FIG. 5 is a top view thereof;

FIG. 6 is bottom view thereof;

FIG. 7 is a rear elevation view thereof;

FIG. 8 is a reduced front and right side perspective view thereof; and,

FIG. 9 is a reduced rear and right side perspective view thereof.

The broken-line disclosure of a chair in the views is for illustrative purposes only and forms no part of the claimed design.
